UNITED STATES PATENT OFFICE

JOHN A. FARNUM, OF WORCESTER, MASSACHUSETTS

ACCOUNT BOOK

Application filed May 25, 1928. Serial No. 280,564.

This invention relates to a book for use in record keeping, of the loose leaf type.

The principal objects of the invention are to provide a construction in which the back 5 of the book can be removed very readily from the mechanical part contained therein, to expose the same for adjustment and repairs; to provide a construction in which the curved rods on which the loose leaves are 10 held can be made longer than has been the case heretofore, thus providing for the efficient holding of a full set of loose leaves and lessening the danger of the upper leaves being accidentally detached and to provide a 15 simplified latch for locking and unlocking the back to permit separation of the two sets of rods.

Other objects and advantages of the invention will appear hereinafter.

20 Reference is to be had to the accompanying drawings in which

Fig. 1 is a plan of a book constructed in accordance with this invention and shown as in normal open position with no sheets in 25 place;

Fig. 2 is an end view of the same partly in cross section on enlarged scale;

Fig. 3 is a plan on enlarged scale of the 30 end of the book illustrating the latch mechanism;

Fig. 4 is a similar view showing the device unlocked;

Fig. 5 is a view similar to Fig. 2 showing the book unlocked and spread out so that 35 the leaves can be inserted or removed;

Fig. 6 is an edge view of a part of the locking mechanism;

Fig. 7 is a plan on enlarged scale showing the position of the rods when the back is 40 locked in closed position;

Fig. 8 is a sectional view taken on the center of one of the rods showing the manner in which the extra length is secured, and

Fig. 9 is a sectional view on the line 9—9 45 of Fig. 8.

The present invention is an improvement on the well known type of loose leaf account book in which the leaves are held in place by rods extending in pairs but alternately from 50 opposite sides of a hinged back. In this type

of book it has been necessary heretofore to take it all to pieces in order to get at the mechanical parts at the back, which is a waste of time and not only involves expense but the loss of a book for a considerable period 55 while being repaired. The rods which hold the loose leaves extend across the space in the back and they have been generally made of a length equal to the thickness of the entire lot of loose leaves when the book is full. 60 Therefore when the book is opened and all the leaves left on one side the natural expansion of the papers, which are pressed together in the book, will bring the leaves to the ends of the rods and make it very easy 65 to displace them and this gives considerable trouble.

This invention, as stated above, is designed to mitigate or overcome these difficulties and to provide an improved latch to hold the two 70 halves of the back together.

In this invention I use the same principles that have been employed before but in an improved form. The book is made up of several elements including two back members 10, hinged together along a center by a hinge pin 11. These are made of sheet metal and are both L-shaped in cross section so that when in closed form, as shown in Figs. 1 and 2, they furnish a rectangular trough 75 80 in which the lower ends of the leaves of the ledger or other book are held.

These two metallic members are locked together in the position shown in these two figures by means of a spring tongue 12 bolted 85 to the side of one of the members 10 and extending outwardly across the hinge to a position part way across the other half. In this position the tongue comes underneath a tooth or catch 13 on a stationary longitudinal member 14 bolted to the other half of the back 10.

Located adjacent to the extreme end of this tongue is a lever 15 pivoted on a screw 16 and having an operating projection 17. 95 When this lever is pulled out to the longitudinal position shown in Fig. 4 the projection 17 pulls the tongue 12 out from under the catch 13. This permits the two halves of the back to be swung apart to the position shown 100

in Fig. 5. The lever 15 is then released and the natural spring of the tongue 12 will pull it back. When the two halves are swung together the lower edge of the tongue 12 will slide down the incline 18 on the stationary catch 13 and the parts will automatically lock themselves together in the closed position.

The two members 10 of the back are connected by screws 20 and nuts 19 with heavy pieces of leather-covered material 21, or other binding material which has a soft outer surface for the book to rest on and spaced from the back by a series of bolt heads 22. Thus these pieces 21 are detachably secured to the back members 10. These strips 21 can be removed by manipulating the screws 20 thus exposing the back for any repairs or other operations that may be required.

As is usual, each one of the backs 10 is provided with a series of rods 25. The rods of the two series alternate with each other as indicated in Figs. 1 and 7. Instead of having these rods terminate just short of the opposite back member 10 I provide a series of perforations 36 through each back member for receiving these rods. These perforations are elongated and provided with a reinforcement around the same if desired. On account of the curvature of the rods at their ends and their penetration through the back members I can make them practically a half inch longer than has been the custom heretofore. On account of this elongation the rods can project through clear to the inner surface of the backing member 21.

When the back is opened, as shown in Fig. 5, the whole body of leaves can be held on one set of these rods and the natural expansion of the leaves, when relieved from pressure, is not likely to bring the top ones up above the tops of these rods. In this way less care has to be exercised to avoid the detachment of the top leaves and the user can bring the whole body of leaves over to one side without this danger. In this way the well-known advantages of detachable leaf books are retained but improvements are introduced in several particulars as stated above.

Although I have illustrated and described only one form of the invention I am aware of the fact that modifications can be made therein by any person skilled in the art without departing from the scope of the invention as expressed in the claims.

Therefore, I do not wish to be limited in these respects but what I do claim is:—

1. In a loose leaf account book, the combination with a hinged back of metal, of a non-metallic covering for each half of the back and detachable means for holding the covering on the back, whereby the covering can be removed at will and the metallic parts exposed for adjustment and repair.

2. In a loose leaf account book, the combination with a metallic back formed of two parts hinged together, of a stiff non-metallic covering for each half of the back partaking of the shape thereof, and removable means for securing the covering to the back on both sides to provide for ready detachment.

3. In a loose leaf account book, a metallic back consisting of two members hinged together, one member having a fixed rigid catch located thereon, the other member having a straight spring tongue projecting a distance across the hinge at right angles thereto between the two members into a position to engage the catch as the book is closed and adapted to spring back under the catch, for holding the book locked in closed position.

4. In a loose leaf book, a metallic back consisting of two members hinged together along the center, one member having a fixed rigid catch located thereon, the other member having a spring tongue projecting across the hinge between the two members into a position to engage the catch as the book is closed, and a pivoted lever on the first-named back member having a projection for engaging the end of the spring tongue and forcing it beyond the catch when said lever is swung to longitudinal position so as to release the two members and permit the opening of the back.

In testimony whereof I have hereunto affixed my signature.

JOHN A. FARNUM.
